(57) CLAIM

() Term: 14 Years

The ornamental design for a lighting apparatus attachable to furniture hinge, as shown and described.

(21) Appl. No.: 29/295,028

DESCRIPTION

(22) Filed: Sep. 20, 2007

FIG. 1 is a plan view of the front of the lighting apparatus attachable to furniture hinge.

(30) Foreign Application Priority Data

Mar. 22, 2007 (DE) 4 07 01 573

FIG. 2 is a plan view of the rear of the lighting apparatus attachable to furniture hinge.

(51) LOC (8) Cl. 26-05

FIG. 3 is a plan view of the left side of the lighting apparatus attachable to furniture hinge.

(52) U.S. Cl. D26/60

FIG. 4 is a plan view of the right side of the lighting apparatus attachable to furniture hinge.

(58) Field of Classification Search D26/60-66,
D26/72, 85; 362/102, 240, 157-159, 183,
362/101, 431, 367

FIG. 5 is a plan view of the top of the lighting apparatus attachable to furniture hinge.

See application file for complete search history.

FIG. 6 is a plan view of the bottom of the lighting apparatus attachable to furniture hinge; and,

(56) References Cited

FIG. 7 is a perspective front right view of the lighting apparatus attachable to furniture hinge.
